UNITED STATES PATENT OFFICE.

WILLIAM MITTERREITER, OF MEMPHIS, TENNESSEE.

GAUGE COCK.

Application filed November 22, 1924. Serial No. 751,626.

To all whom it may concern:

Be it known that I, WILLIAM MITTERREITER, a citizen of the United States, residing at Memphis, in the county of Shelby and

State of Tennessee, have invented a new and useful Gauge Cock, of which the following is a specification.

This invention relates to a gauge cock, adapted to be used for controlling the discharge of steam or other fluid.

The object of the invention is to provide a device for the purpose stated, which is simple in its construction, quick acting and easily operated, and which is so constructed that the interior is readily accessible for the purpose of cleaning the same.

The structural details of the invention and the advantages thereof will be more particularly described in connection with the accompanying drawing, which illustrates the invention in its preferred form.

In the drawing:

Figure 1 is a longitudinal vertical section through the invention.

Figure 2 is a transverse section taken on the line 2—2 of Figure 1.

Figure 3 is a horizontal section taken on the line 3—3 of Figure 1.

Figure 4 is a section taken on the line 4—4 of Figure 1.

Figure 5 is a perspective view of the valve actuating rod.

Referring in detail to the drawing, the gauge cock embodying my invention comprises a stem 6, having a threaded end 7 adapted to be screwed into a threaded hole tapped into a steam boiler, or other receptacle from which fluid is to be discharged. The stem 6 is formed with a central passageway 8, and is formed at its outer end with an enlarged portion 9, having a transverse cylindrical bore 10 adapted to be arranged vertically, and to form a valve chamber. Adjacent the enlarged portion 10, the stem is formed with a polygonal portion 11, to which a wrench may be applied for attaching the gauge cock to the boiler or other receptacle.

A nipple 12, preferably of brass, forms a steam tight fit in the lower part of the bore 10, beneath the outlet of the passageway 8, and has a restricted central bore 13, the upper end of which is enlarged to form a conical valve seat 14, which is adapted to receive a spherical ball valve 15. The upper end of the bore 10 is closed by a flanged

plug 16, having a pair of opposed ears 17 projecting from its upper end, transversely of which is secured a pin or bolt 18. A handle 19 is pivotally mounted on the pin or bolt 18, and has a laterally projecting arm 20, which terminates in a fork 21, adapted to straddle the reduced portion 22, formed near the upper end of a vertically disposed valve operating rod 23. This rod has its lower end bent laterally, as at 24, and terminating in an upturned end 25, which is adapted to extend upwardly in the bore 13 and, when the rod is raised, to engage the ball valve 15 and raise the same, as indicated by dotted lines in Figure 1, permitting the steam or other fluid to be discharged. A vertical bore 26 is formed in the outer portion of the gauge cock for receiving the vertical portion of the rod 23, and its upper end is closed by a gland 27, through which the upper end of the rod projects. A slot 28 extends laterally from the lower end of the bore 26, and a similar slot 29 is formed in the side of the nipple 12 for receiving the horizontal portion 24 of the valve operating rod, and permitting the vertical movement thereof. A nozzle 31 forms the outlet for the gauge cock, and has a threaded connection with the lower end of the nipple 12. It is provided with a horizontal flange 32, which may be welded or otherwise secured to the lower end of the enlarged portion 9 of the stem, so as to close the lower edge of the slot 28, and to form a seat which limits the downward movement of the rod 23.

In the operation of the gauge cock, whenever it is desired to open the valve, the handle 19 is moved toward the dotted line position shown in Figure 1, thereby raising the rod 23, and the upturned end 25 thereof engages the lowermost part of the ball valve 15 and opens the same. Upon release of the handle 19, the ball will drop to its seat 14 by gravity, and will be held firmly thereon by pressure. In order to clean the gauge cock, it is only necessary to remove the pin or bolt 18 and the handle 19, whereupon the plug 16 may be unscrewed, and the interior of the gauge cock may be easily cleaned without removing the same from the boiler. The ball valve 15 is self-cleaning, and it is never necessary to grind the valve or its seat. The handle 19 and the plug 16 may be removed without disturbing the position of the valve on its seat. The brass nipple, which forms the valve seat, is pro-

vided at its upper end with a flange 33, which is preferably brazed or soldered to the wall of the bore 10, so as to prevent any possibility of leakage. It will thus be seen that the invention is very simple in construction, and there is very little to get out of order. It may be manufactured at a moderate cost, and may be used with either steam or water, or other liquid under pressure.

While I have shown and described in detail the specific construction of the invention in its preferred form, it is apparent that various modifications may be made in the relative size and arrangement of the various elements without departing from the salient features of the invention, or sacrificing any of its advantages. It is my desire, therefore, to include all such modifications within the scope of the appended claims.

What is claimed is:

1. In a gauge cock, the combination of a valve chamber provided with an inlet and an outlet passageway, a valve in said chamber normally closing the outlet, the wall of said valve chamber having a bore substantially parallel to the outlet passageway with a slot connecting the bore to said passageway, a valve operating rod mounted for reciprocation in said bore with its inner end portion turned laterally and extending through said bore and terminating in a return bent end engageable underneath the valve, means operatively connected to the outer end of the rod to actuate the same to open the valve, and a packing gland surrounding said rod at the outer end of the bore to prevent leakage.

2. In a gauge cock, the combination of a stem having an enlarged portion with a vertical bore forming a valve chamber, an outlet nipple secured in the lower part of said bore and formed with a valve seat, said enlarged portion having a smaller vertical bore at one side of the valve chamber, and a slot connecting the smaller bore with the outlet through the nipple, a valve normally engaging said seat, a valve operating rod reciprocably mounted in said smaller bore and having its lower end portion extending through said slot and terminating in an upturned end beneath the valve, and means associated with the upper end of said rod for raising the same to open the valve.

3. In a gauge cock, the combination of a housing having a vertical bore forming a valve chamber, an outlet nipple secured in the lower part of said bore and formed with a valve seat, said housing having a smaller vertical bore at one side of the valve chamber, and a slot connecting said smaller bore with the outlet through the nipple, a valve normally engaging said seat, a valve operating rod reciprocably mounted in said smaller bore and having its lower end portion extending through said slot and terminating in an upturned end beneath the valve, a removable plug forming the upper wall of the valve chamber, and a handle pivotally mounted on the plug and having a laterally extending arm operatively connected to the upper end of the rod so as to raise the same to open the valve.

In testimony, that I claim the foregoing as my own, I have hereto affixed my signature.

WILLIAM MITTERREITER.
